UNITED STATES PATENT OFFICE.

LINCOLN GERHARDT, OF WASHINGTON, DISTRICT OF COLUMBIA.

LAMP OR LANTERN LIGHTING DEVICE.

SPECIFICATION forming part of Letters Patent No. 410,238, dated September 3, 1889.

Application filed December 11, 1888. Serial No. 293,263. (No model.)

To all whom it may concern:

Be it known that I, LINCOLN GERHARDT, a citizen of the United States of America, residing at Washington, in the District of Columbia, have invented certain new and useful Improvements in Lantern or Lamp Lighting Devices, of which the following is a specification, reference being had therein to the accompanying drawings.

10 My invention relates to improvements in lighting devices for lanterns or lamps in which the chimney is perforated to permit the introduction of a match therein; and the objects of my improvement are to provide lanterns or lamps of this class with simple and inexpensive means to permit a match to be ignited within the chimney, and thereby sheltered from the wind. I attain these objects by the construction illustrated in the accompanying drawings, in which—

Figure 1 is a vertical section of a lantern provided with a match-lighting device constructed in accordance with my invention. Fig. 2 is a side view of a lamp also provided with means to light it in accordance with my invention. Fig. 3 is a perspective view of a portion of the chimney or globe supporting plate, showing the friction-plate and the globe-stopper attached thereto. Fig. 4 is a perspective view of the friction-plate and its support detached.

In said drawings, A represents an oil-reservoir provided with a burner B, having a slot b in the top thereof for the passage of the wick C and of the flame fed thereby. Said burner has a perforated horizontal plate D, as usual, upon which rests the globe E of a lantern or the chimney E of a lamp. The globe is retained in a vertical position by means of wires e, encircling its upper end and attached to the frame of the lantern, and the chimney of the lamp is retained by means of spring-fingers e², attached to the burner or to its base-plate.

45 To permit the wick of the burner to be lighted without removing or detaching the globe from its support and igniting a match within said globe, and have it thus protected from the wind that may be blowing, the globe has a perforation f made in its side substantially upon a horizontal line passing through the

slot b of the burner. Said perforation, being fully a quarter of an inch in diameter, permits the lighting end of a match m to be readily introduced into the globe at that point and 55 pushed in until it comes in contact with the wick.

To light the match within the globe, there is attached to the burner or to its base-plate D a serrated or frictional surface in the form 60 of a light rectangular plate g, having its ends bent down and provided with a tongue g², that is inserted in perforations of the plate D or of the burner and clinched against the under side thereof. As the plate g has its two ends 65 secured to its support, it can be made of thin sheet metal, as tinned sheet-iron, which is inexpensive and easily perforated to produce a rasp-like surface. The top of the plate g is provided with a surface of emery made to adhere thereto or with a rasp-like surface; or the long edges of the top of the plate g may be bent over to form grooves to receive the edges of a plate g³, having a rasp-like surface made by partly punching the metal of said 70 plate or otherwise.

To prevent the wind from entering the globe of the lantern through the perforation f, a shutter h, preferably circular, is retained on the same level as said perforation by means 80 of a wire e⁴, attached in the middle of its length to said shutter and having its ends inserted in perforations of the plate D and bent over to clasp it. When used on a lamp, the shutter h is attached to one of the clamping-fingers e² of the burner. When it is desired 85 to light the lamp or lantern, the globe is rotated a short distance until its perforation f comes in line with the frictional surface g and with the slot b of the burner. A match 90 is then inserted and rubbed upon said rough surface. It then becomes ignited and is pushed forward until it comes in contact with the wick and ignites the latter. The match is then withdrawn and extinguished and the 95 globe rotated a small portion of a turn until the perforation f coincides with the stationary shutter h.

I am aware that lamp-burners have been provided with a tube entering through the 100 bottom thereof and that a frictional blade has been attached to the end of said tube,

against which one end of a match can be forced to ignite it, but they differ from my construction.

Having now fully described my invention,
5 I claim—

1. A lamp-burner in which one of the chimney-retaining springs is provided with an enlarged portion adapted to cover an aperture formed in the chimney or globe, in combination with a chimney or globe provided with an aperture in the side and adapted to be turned, substantially as described.
2. The combination of an oil-reservoir, a lamp-burner and its glass globe provided with 15 a perforation therein on the same level with said burner, a frictional plate secured at both of its ends to the globe-supporting plate of

the burner, and a shutter secured to said supporting-plate, substantially as and for the purpose described.

3. The combination of a chimney or globe having a perforation in the side thereof with a lamp-burner having one of its chimney or globe retaining springs provided with a disk or enlarged portion and with a roughened 25 plate secured at both ends to the burner, substantially as set forth.

In testimony whereof I affix my signature in presence of two witnesses.

LINCOLN GERHARDT.

Witnesses:

E. E. MASSON,
HARRY L. AMER.
